UNITED STATES PATENT OFFICE.

CHRISTOPHER C. KILTS, OF HANNIBAL, MISSOURI.

CAR-DOOR FASTENING.

SPECIFICATION forming part of Letters Patent No. 252,384, dated January 17, 1882.

Application filed October 29, 1881. (No model.)

To all whom it may concern:

Be it known that I, CHRISTOPHER C. KILTS, of Hannibal, Missouri, have made a new and useful Improvement in Railway-Car-Door Fasteners, of which the following is a full, clear, and exact description, reference being had to the annexed drawings, making part of this specification, in which—

Figure 1 is a side elevation, showing that portion of the car with which the improvement in question is immediately connected; and Figs. 2, 3, 4, and 5, details, being views in perspective, and respectively, of a portion of the forward edge of the car-door as held in the fastening-clip, of the lower rear corner of the door and parts immediately therewith connected, the door being closed, of the lower rear corner of the door and the parts immediately therewith connected when the door is opened, and of the forward end of the bar used in locking the door when closed.

The same letters denote the same parts.

The present device is valuable in that by means of it a sliding door can be fastened and unfastened more readily, and, when closed, be shut closer than by the modes of fastening commonly in use.

It consists mainly in a bar pivoted to the side of the car at or toward that end thereof toward which the door, in opening, slides; and so that when the door is opened the bar can be turned upward out of the way of the door, and when the door is closed be turned down into a horizontal position to operate as a brace to prevent the door from opening. The bar also serves, in connection with clips upon the side of the car, to wedge the door laterally and so as to close tightly the joint between the door and the side of the car.

Referring to the drawings, A represents the side of a freight-car of the usual construction, saving as modified by the present improvement.

B represents the door, having the hangers b b, and sliding upon the rail C, in the customary manner, the direction of movement being indicated by the dotted lines in Fig. 1.

D represents a bar, pivoted at d to the side of the car, and capable of being turned from the position shown in the full lines in Figs. 1

and 2 upward into the position shown in the full lines in Fig. 4 and indicated by the dotted lines in Fig. 1.

To close the door and fasten it, the door is moved until opposite the doorway, and then the bar D is turned upon its pivot d down into the position shown in Figs. 1 and 2, bringing the end d' of the bar against the rear end or edge, b', of the door, pressing the latter endwise and forcing its forward end, b², against and into the clip E, the clip serving as a stop and also to hold the forward end, b², of the door closely against the side of the car. For this last-named purpose the projection E of the clip is shaped and extended so as to deflect the end b² as it enters the clip, toward the side of the car. At the same time the rear end, b', of the door is forced closely against the side of the car, as follows: The bar D, at its end d', is furnished with a plate or piece, d², which projects beyond the end of the bar, and to come, when the bar is turned down, inside a clip, F, that is attached to the side of the car, and operates as a wedge to crowd its end b' against the side of the car.

The wedging may be effected by making the projection d² wedge-shaped in cross-section, as shown more distinctly in Fig. 5, or by inclining or beveling the projection f of the clip F, as seen more distinctly in Fig. 3; or both means can be used in conjunction.

In opening the door the bar D is turned up into the position shown in Figs. 4 and 1 and the door moved back until its rear end, b', abuts against the bar, as seen in Fig. 4. The clip G serves to confine both the bar and the door when the latter is opened, operating as a stop and also to confine the bar when upturned and before the door is opened.

I claim—

1. The combination of the side A, the door B, the bar D, having the projection d², and the clip F, substantially as described.

2. The combination of the side A, the door B, the bar D, having the projection d², and the clips E and F, substantially as described.

CHRISTOPHER C. KILTS.
